DESIGN FOR A PREMIUM COUPON

Albert A. Plock, Eminence, Ky.

Application March 13, 1940, Serial No. 90,901

Term of patent 3½ years

To all whom it may concern:

Be it known that I, Albert A. Plock, a citizen of the United States, residing at Eminence, in the county of Henry and State of Kentucky, have invented a new, original, and ornamental Design for a Premium Coupon, of which the following is a specification, reference being had to the accompanying drawing, forming part thereof.

I claim:

The ornamental design for a premium coupon, as shown.

ALBERT A. PLOCK.
